W. STIEBER

FLYING MACHINE PROPELLER

Filed May 5, 1921

FIG.1. FIG.2. FIG.3.

INVENTOR:

*Max Abramowski

Wilselma Miller.

UNITED STATES PATENT OFFICE.

WILHELM STIEBER, OF AMBERG, GERMANY, ASSIGNOR TO THE FIRM: RUPPEL BROS.
METALLWARENFABRIK, OF GOTHA, GERMANY.

FLYING-MACHINE PROPELLER.

Application filed May 5, 1921, Serial No. 466,973, and in Germany October 1, 1918.

My invention refers to metallic propellers for aerial vehicles and more especially flying machines and its particular object is to provide a metal propeller of superior resistivity 5 against the action of centrifugal force.

In order to combine lowest possible weight, highest security of working and greatest efficiency, the blades of the propeller according to the present invention are 10 formed of any suitable number of superposed metal plates, these said plates being cut out in the places, where they overlap one another, in such wise that each blade forms a body of substantially uniform 15 strength throughout.

The propeller thus forms a hollow body composed of two cup-shaped parts consisting of sheet metal, the one part forming the pressure side, the other one the suction side. 20 The pressure side, instead of being formed of a single plate, is composed of a plurality of plates placed stepwise one upon the other, the number of plates increasing in the direction towards the axis in proportion to the 25 increasing strain. Instead of being cut off straight, the single plates are provided with indentures of substantially triangular form, such indentures providing that a uniform load is placed on the plates throughout the 30 length of the blade.

In the drawings affixed to this specification and forming part thereof a propeller embodying my invention is illustrated by 35 way of example in a purely diagrammatic manner.

In the drawings

Fig. 1 is a front view, and

Fig. 2 a side elevation of one blade, while

Fig. 3 is a longitudinal section on the 40 line I—I in Fig. 1.

Referring to the drawings, each blade has the form of a hollow sheet metal body. According to my invention that part of the blade which forms the suction side, when

the propeller is running, is made of a single 45 metal plate. In contradistinction thereto that portion which acts as pressure side, is formed of a plurality of metal plates, three such plates *c*, *b*, *a* being provided in the case disclosed in the drawings, these plates 50 being superposed and interconnected so as to form near the basis of the blade a reinforced portion of triple strength. The plates *c*, *b*, and *a* differ in length, plate *c* extending from the blade basis only over 55 about one-fourth of the entire length of the blade and forming the innermost layer, whereas the middle plate *b* extends over about three-fifths of the entire length, only the outermost plate *a* having full length. 60 Obviously this arrangement of plates of different length corresponds to the different strains exerted by the centrifugal forces upon the different portions of the blade. In order to still more effectively relieve the 65 blade, the two shorter blades *c* and *b* are cut out from their ends down to about half their length, narrow triangular indentures *e* and *f* being formed in the blades *c* and *b*, respectively, whereby the stresses acting on the 70 plates in different parts of their length are nearly equalized.

Obviously my invention is by no means restricted to a blade composed of three superposed plates of different length nor to 75 any particular form of indenture.

I claim:

A hollow sheet metal aircraft propeller comprising hollow blades, a portion of each blade being formed of a plurality of superposed metal plates of different length rigidly connected with one another and cut out triangularly so as to equalize the centrifugal stresses exerted on different portions of each propeller blade. 80

85 In testimony whereof I affix my signature.

WILHELM STIEBER.
